UNITED STATES PATENT OFFICE.

MORTIMER B. MILLS, OF CHICAGO, ILLINOIS.

RAILROAD-GATE.

SPECIFICATION forming part of Letters Patent No. 424,074, dated March 25, 1890.

Application filed January 20, 1890. Serial No. 387,509. (No model.)

To all whom it may concern:

Be it known that I, MORTIMER B. MILLS, a citizen of the United States, residing at Chicago, in the county of Cook and State of Illinois, have invented a new and useful Improvement in Railroad-Gates, of which the following is a specification.

My invention relates to an improvement in the class of gates commonly provided at railway-crossings, and comprising vertically-swinging arms on posts and actuated by pneumatic pressure.

The object of my invention is to provide simple mechanism, both as to construction and cost, and which is reliably and readily operative, for producing by pneumatic force the raising and lowering of the arm or arms of the gate.

In the accompanying drawings, Figure 1 is a view in broken sectional elevation of a railroad gate provided with my improvement applied to a gate formed with two posts carrying counterbalanced arms connected underground to cause the raising or lowering of one to produce simultaneously the raising or lowering of the other, and Fig. 2 a view in elevation of a detail.

A and A' are hollow gate-posts of ordinary or any suitable general form and construction, and B and B' are the counterbalanced arms supported, respectively, by the said posts on shafts C, journaled in the posts near their upper ends, and to which the gate-arms are secured. Each shaft C has integral or cast with it between its ends a larger pulley D, which should be peripherally grooved, as shown, and at or on one of its sides a smaller pulley D', which should also be peripherally grooved, but of which only one-half, as shown, or an even smaller segment, is required.

E and E' are bell-cranks, each pivoted at its angle inside a gate-post on a shaft r, journaled in the opposite sides of the post, near the rear or outer side thereof, the bell-cranks in the two posts being so adjusted as to cause their arms q to extend in opposite directions or toward each other. The bell-crank E is connected from its arm q, by a chain p or analogous connecting medium, with the segment D' in the post A, and the arm q of the bell-crank E' is similarly connected, by a chain p' or the like, with the adjacent seg-

ment D', the connecting-chains p and p' being adjusted to extend in the same direction about the peripheries of the segments D' and 55 fastened to the farthest extremities thereof. In their relatively normal positions the arrangement of parts is preferably such as to cause the straight side of one of the semi-circular segments D' to extend vertically, as 60 shown at the right-hand side in Fig. 1, while that of the other, as shown at the left-hand side thereof, extends horizontally.

The arms B and B' are connected together underground in a manner to cause the raising or lowering of one to raise or lower with it the other. To effect such operation I prefer to employ the means illustrated, comprising a tube F, embedded in the ground and extending from one post to the other, 70 being provided at its opposite extremities with water-tight chambers F', each of which has journaled within it a pulley o, a rod n in the tube, and chains m and m', or the like, extending from the opposite ends of the rod 75 about the pulleys o through tubes F², projecting vertically from the chambers F' into the bases of the posts A and A', the chains being extended in the same direction upon and secured at their extremities, as shown, 80 to the peripheries of the pulleys D. Of course the chains m and m' may be a continuous chain connecting the pulleys D through the underground tube F, thereby dispensing with the rod n, though the construction shown is preferable.

Adjacent to the inner sides of the posts A and A', near their bases, are supported the collapsible air-receivers G and G', each of which may be of the common construction 90 illustrated, and comprising a shell having clamped between the edges of its two halves a diaphragm l, of elastic material, (preferably rubber and canvas in alternate layers,) such or substantially such as is shown in Letters 95 Patent of the United States No. 387,435, granted me on the 17th day of April, 1888.

Rods k, secured each at one end to the center of the diaphragm in their respective receivers G and G', extend through the shells 100 of the latter and adjacent sides of the posts A and A' into coincidence with the ends of the depending arms q' of the bell-cranks E and E', and are pivotally connected with the

same, as shown. Each collapsible receiver device (which thus forms a species of piston mechanism) communicates from the inner side of its shell through a pipe i with a four-way valve h , (of well-known construction, and therefore not illustrated in detail,) into which extends the supply-pipe g from an air-pump H or other source of pneumatic pressure. Other arrangement of controlling-valves between the pump and pipes l' may be used instead of the four-way valve h .

To lower the gate-arms from the raised positions at which they are indicated in Fig. 1, the valve h is turned to produce communication of the receiver G' with the pump and of the receiver G with the open air, when the pump is actuated to exert air-pressure against the diaphragm of the receiver G' , thereby forcing the piston-rod k thereof against the arm q' of the bell-crank E' , which lowers the arm q thereof, pulling the chain p' downward and turning the respective segment D' in the direction to produce lowering of the gate-arm B' . This turning of the said segment D' causes the pulley D to draw upon the chain m' , and thus through the underground connection turn the pulley D of the post A in the direction to lower the gate-arm B .

To raise the gate-arms, the valve h is adjusted to direct the air-pressure against the diaphragm of the receiver G , causing its piston-rod k to force the arm q' of the bell-crank E outward and the arm q downward, with the effect of drawing upon the chain p to turn its segment D' in the direction to effect raising of the arm B , and thereby turning the respective pulley D to draw the underground connection in the direction in which it turns the pulley D of the post A' to raise the arm B' .

The vertically-projecting tubes F^2 extend sufficiently high inside the gate-posts to be beyond the water-line of any water that may accumulate in the posts, thereby preventing the access of moisture to the underground mechanism and consequent injury thereto by freezing.

Where a gate is composed of a single swinging arm on a post, which arm should then be weighted at one end, of course but one collapsible receiver, piston-rod, bell-crank and shaft, with its smaller pulley device, is required, and in that case, obviously, the underground connection is not needed. Such construction is intended to be included in my improvement.

What I claim as new, and desire to secure by Letters Patent, is—

1. In a gate, the combination of a hollow post, a swinging arm supported on a shaft C , journaled in the post and carrying a pulley D' , a bell-crank pivotally supported inside the post and having its arm q connected with the said pulley by a chain or the like, a collapsible air-receiver having a rod k , secured at one end to its diaphragm and at its opposite end to the arm q' of the bell-crank, and air-

pressure mechanism communicating with the said collapsible air-receiver, substantially as described.

2. In a gate, the combination of a hollow post, a swinging arm supported on a shaft C , journaled in the post and carrying a pulley D' , a bell-crank pivotally supported inside the post and having its arm q connected with the said pulley by a chain or the like, a collapsible air-receiver supported outside the post near its base, a rod k , secured at one end to the diaphragm of the said receiver, passing thence into the post and pivoted at its opposite end to the arm q' of the bell-crank, and an air-pump H , communicating controllably with the said collapsible air-receiver, substantially as described.

3. In a gate, the combination of the hollow posts A and A' , having journaled in them the shafts C , carrying inside the post pulleys D , connected underground between the posts and pulleys D' and supporting the arms B and B' , bell-cranks E and E' , pivotally supported, respectively, in the posts A and A' and connected from their arms q with the pulleys D' , collapsible air-receivers G and G' , each having a rod k , secured at one end to its diaphragm, and at its opposite end to the arm q' of a bell-crank, and air-pressure mechanism communicating controllably with the collapsible air-receivers, substantially as described.

4. In a gate, the combination of the hollow posts A and A' , having journaled in them the shafts C , each carrying inside its posts pulleys D and D' and supporting the arms B and B' , a tube F , extending underground between the posts and having chambers F' at its opposite ends, containing pulleys o , means, substantially as described, connecting the pulleys D through the tube F and chambers F' , bell-cranks E and E' , pivotally supported, respectively, in the posts A and A' and connected from their arms q with the pulleys D' , collapsible air-receivers G and G' , each having a rod k , secured at one end to its diaphragm and at its opposite end to the arm q' of a bell-crank, and air-pressure mechanism communicating controllably with the collapsible air-receivers, substantially as described.

5. In a gate, the combination of the hollow posts A and A' , having journaled in them the shafts C , each carrying inside its post pulleys D and D' and supporting the arms B and B' , a tube F , extending underground between the posts and having chambers F' at its opposite ends, containing pulleys o , tubes F^2 , extending from the said chambers into the posts, means, substantially as described, connecting the pulleys D through the tubes F and F^2 and chambers F' , bell-cranks E and E' , pivotally supported, respectively, in the posts A and A' and connected from their arms q with the pulleys D' , collapsible air-receivers G and G' , each having a rod k , secured at one end to its diaphragm and at its opposite end to the arm q' of a bell-crank, and air-pressure mechan-

ism communicating controllably with the said collapsible air-receivers, substantially as set forth.

6. A gate comprising, in combination, hollow posts A and A', shafts C, journaled in the posts and having each as integral parts thereof a pulley D and a pulley D', arms B and B', supported on the said shafts, a tube F, extending underground between the posts and having chambers F' at its opposite ends, containing pulleys o, tubes F², extending from the said chambers into the posts, a rod n in the tube F, chains m and m', or the like, respectively connecting the pulleys D with opposite ends of the rod n and passing through the tubes F² and over the pulleys o in the chambers F',

bell-cranks E and E', pivotally supported, respectively, in the posts A and A' and connected from their arms q with the pulleys D', collapsible air-receivers G and G', supported near the bases of the posts and each having a rod k, secured at one end to its diaphragm, extending thence into a post and pivotally connected therein at its opposite end with the arm q' of a bell-crank, and an air-pump H, communicating controllably with the said collapsible air-receivers, substantially as described. 20 25
